UNITED STATES PATENT OFFICE.

CHARLES A. HALSTEN, OF BILLINGS, MONTANA, ASSIGNOR TO C. J. VOLLMER, OF BUTLER, PENNSYLVANIA.

AUTOMOBILE RADIATOR.

Application filed June 7, 1921. Serial No. 475,569.

To all whom it may concern:

Be it known that I, CHARLES A. HALSTEN, a citizen of the United States, residing at Billings, county of Yellowstone, State of Montana, have invented certain new and useful Improvements in Automobile Radiators; and I do hereby declare the following to be a full, clear, and exact description of the invention, such as will enable others skilled in the art to which it appertains to make and use the same.

The present invention relates to improvements in automobile radiators, and has for an object to provide a coil construction disposed between two headers to avoid the complicated mesh structure as heretofore produced and to render each coil independently removable from the headers so that repairs may be more expeditiously and economically made without requiring the dismantling of the entire radiator.

Another object of the invention resides in providing an improved jointed structure between the ends of the coils and the headers forming a substantially leak-proof union and providing an assembly which may be applied to existing forms of radiator headers without requiring substantially any modification or alteration therein.

Further objects of the invention are to provide an inexpensive radiator construction having a comparatively large surface exposure to the cooling air in order that the water may at all times be kept cool and an active circulation promoted such as will prevent any likelihood of overheating or of abnormal temperatures in the motor.

With these and other objects in view the invention consists in the novel details of construction and combinations of parts more fully hereinafter disclosed and particularly pointed out in the claims.

In the accompanying drawings forming a part of this application, and in which similar reference symbols indicate corresponding parts in the several views:

Figure 1 is a vertical section of an improved radiator constructed according to the present invention.

Fig. 2 is a horizontal section of the same. Fig. 3 is an enlarged cross sectional view of a portion of the radiator and one of the coils showing the improved union; and

Fig. 4 is a fragmentary perspective view of a section of one of the coils.

55

Referring more particularly to the drawings, wherein only a single embodiment of the invention is disclosed, the improved radiator consists of a pair of headers 1 and 2 which are preferably disposed vertically one above the other with an intermediate space occupied by a number of coils 3 which communicate at their ends respectively with the two headers and form a portion of the circulatory system therewith. The upper header 1 is provided with the usual filling nut 4 closed by the screw or other cap 5 and it also is equipped with a short neck of pipe 6 to which is attached the hose, coupling the radiator with one portion of the water jacket 70 of the engine. The lower radiator 2 is in a similar manner formed or otherwise produced with a short section 7 of pipe neck adapted to couple to the hose extending to the lower portion of the engine water jacket, 75 the circulation of the water taking place in the usual way.

A mesh 8 is preferably stretched across in front of the coils 3 between the headers 1 and 2 and the mesh may be of any suitable design, for instance to simulate the front portions of the usual automobile radiators. The meshes are, of course, suitably large to permit of the passage of a necessary quantity of air to the coils 3. In some cases it 85 may also be desirable to stretch a screen or mesh fabric 9 between the headers 1 and 2 in rear of the coils 3, such mesh fabrics 8 and 9 further forming protecting guards for the space between the headers to avoid the 90 entrance of foreign matter which is apt to be encountered in the travel of the vehicle. The meshes will be so arranged as to be readily removed or partially detached to give access to the coils 3 for the purpose of 95 their removal or repair.

In Fig. 3 I have illustrated an improved union between the lower wall 10 of the upper header 1 and one of the coils 3. In accordance with this construction an opening 11 100 is made in the base 10 for each of the coils employed and nipples 12 are let down through this opening from the top, they being provided with flanges 13 which take against the inside face of said part 10. Solder, indicated at 14, is preferably employed

105

- to secure the flange 13 permanently and non-rotatively to the wall 10. The nipples are each threaded exteriorly at their lower ends as indicated at 15, which ends project beneath the horizontal plane of the wall 10 and the lower ends of the nipples are formed with beveled faces 16 which are substantially frusto-conical to receive the similarly formed cone frustum 17 on a head carried by the upper end of the coil 3. An inversely formed conic frustum 18 is formed on the lower portion of the head having its base coincide with the base of the frustum 17 and in effect being an extension thereof in a reverse sense. The latter conic frustum 18 is adapted to take against a similarly formed wall 19 of a packing gland nut 20 having internal screw threads to engage with the threads 15 on the nipple. The nut 20 is flanged as indicated at 21, and snugly grips the coil 3 just below the head. The flange 13 of the nipple is preferably provided with straight line faces in order to receive a wrench or other tool to hold it against turning when the nut 20 is screwed upon the threads 15, but this is only necessary when the nut is applied before soldering the nipple to the header.

As shown more particularly in Fig. 4 the coils 3 are each formed of spirally wound convolutions in any suitable number, the convolutions being flat or elongated in one direction and having their major axes preferably extending vertical so that the sides or flat portions of the coils are presented to the air currents entering through the screen 8. This affords a greater surface area for the cooling air to impinge against and results in the rapid falling of the temperature of the water in the coils.

As shown in Fig. 2 the coils 3 are preferably mounted in two separate rows extending transversely of the vehicle and the coils of the respective rows being arranged in staggered relation. The coils are spaced apart transversely so that the air may enter between adjacent coils of the front row to strike the vertically elongated and flat walls of the convolutions of the rear coils which lie just behind the spaces between said front coils. The coils as shown in Fig. 1, preferably have their convolutions open or arranged on a relatively wide pitch, this for the purpose of providing large air spaces in and about the coils for the rapid circulation of the cooling air. This air is, of course, received in great quantities owing to the width and breadth of the radiator and to the speed of the vehicle, and it is desirable to have the coils so arranged that they will permit of a rapid interchange of air. Particularly is this desirable in hot weather when the temperature of the air consequent upon the interchange of the heat will rise in temperature. It is therefore necessary to

have this heated air released as rapidly as possible to avoid interference with the incoming of cooler fluid.

In use, the water in the circulatory system will become heated in the water jackets 70 of the engine and will gradually rise as it increases in temperature until it passes out through the hose and into the upper header 1. Here it is relieved of the heating influence of the motor and is allowed to descend 75 in the coils 3 where it comes under the cooling influence of the air. As its temperature falls the water further descends in the coils 3 until it arrives at the lower header 2 when it is in an initially cool state ready to pass 80 back into the lower portion of the water jacket to be again circulated therethrough and utilized for cooling purposes. With the arrangement of the coils mounted in staggered relation and with open convolutions 85 subject to a large amount of air currents and by reason of the flat nature of the helix, the water will be more quickly reduced in temperature and more effectively cooled and will result in a more rapid circulation of 90 water through the system, preventing at all times, even in the hottest climates and temperatures, the boiling of the water or its rise above a desirable temperature. Of course this will be followed by a better ac- 95 tion of the motor.

Whenever repairs become necessary the front screen 8 is removed or swung aside to give access to the coils and the injured coil may be quickly detached by unscrewing the 100 gland nut 20 from the nipple 12. The nut may be slid along the coil, a suitably large and comparatively straight neck being provided to permit the upper end of the nut 20 to clear the lower end of the nipple. The 105 coil is preferably formed of some such metal as copper having a slight springing action or at least possessing sufficient ductility to permit of a slight bending of the neck or a springing thereof in removing the upper 110 conic frustum 17 from the beveled end 16 of the nipple.

The lower ends of the coil are preferably secured in the lower header 2 in a similar manner to that shown in Fig. 3 for the upper 115 header and, if desired, the lower end of the coil may in a similar manner be removed.

In this case the entire coil with its head and packing nut gland forms a unitary assembly which may be substituted or replaced 120 by a like assembly, and the assembly just withdrawn may be retained at a repair shop for inspection and repair at leisure.

The conic frustums 17 and 18 form in conjunction with the end of the nipple and the 125 wall 19 of the packing nut an effective seal and a readily detachable union, and if desirable like packing may be placed between the faces; for instance, the faces 18 and 19. The formation of the faces 16 and 17 will 130

also assist in the movement of the coil head out of the nipple.

Having thus described my invention, what I claim as new and desire to secure by 5 Letters Patent of the United States, is:

1. An improved radiator comprising headers, coils extending between the headers and in communication therewith, said coils being composed of convolutions made substantially flat in a direction at right angles to the direction of movement of the air currents thereagainst, and means whereby the 10 headers may be connected in the circulatory system of the motor.
- 15 2. An improved radiator comprising spaced apart headers having means to include them in the circulatory system of a motor, and a number of coils extending between and in communication with the 20 headers and being exposed to cooling fluid currents, said coils being composed of a

suitable number of convolutions wound on a substantially wide pitch having large spaces between and about them for the circulation of the cooling fluid, said convolutions being also elongated in a direction at right angles to the directions of movement of the cooling fluid currents. 25

3. An improved radiator comprising a pair of headers spaced apart and included in the circulatory system of an internal combustion engine and a plurality of rows of coils connected between and communicating with the headers, said coils being spaced apart and the coils of the respective rows 30 being arranged in relatively staggered relation whereby to expose all of the coils to the action of the cooling air currents, the convolutions of the coils being made open and with flat faces presented to the air current. 35

In testimony whereof, I affix my signature. 40
CHARLES A. HALSTEN.
